Attn:

UNITED STATES PATENT OFFICE.

TALBOT G. MARTIN, OF CHICAGO, ILLINOIS, ASSIGNOR TO AUTOMATIC ELECTRIC COMPANY, OF CHICAGO, ILLINOIS, A CORPORATION OF ILLINOIS.

AUTOMATIC TELEPHONE SYSTEM.

Application filed July 3, 1920. Serial No. 393,892.

To all whom it may concern:

Be it known that I, TALBOT G. MARTIN, a citizen of the United States of America, and a resident of Chicago, Cook County, 5 and State of Illinois, have invented certain new and useful Improvements in Automatic Telephone Systems, of which the following is a specification.

My invention relates in general to automatic telephone systems in which connections are established through the medium 10 of subscriber controlled selector and connector switches, but is more particularly concerned with such automatic telephone 15 systems as include party lines and selective ringing equipment at the central exchange; and the object of the invention may be stated to be, broadly, the provision of a new and improved automatic party line 20 selective ringing system.

Numerous methods of selectively ringing automatic party lines have been devised before this. A system in wide use, which is disclosed in the U. S. patent to Goodrum, 25 No. 1,156,475, involves the provision of different frequencies of ringing current at the exchange and tuned bells at the subscribers stations. The connector switches are divided into groups and each party line is 30 accessible to as many different groups of connectors as there are stations on the line, the connectors of each group being adapted to use a different frequency of ringing current for signalling purposes. Each station 35 on a party line is given a separate telephone number, but all the numbers on a given line are the same except for the third from the last digit which, as is well known, is the digit used to control the second selectors 40 in the selection of connector groups. Thus a party line which has, we will say, four stations connected thereto can be reached by four different routes, corresponding to as many different telephone numbers; and 45 the number selected for use when the line is called will determine the route, or the group of connectors to be used, and therefore the particular station on the line which is to be signalled.

As before stated, systems of the foregoing general description have gone into extended use and have given very satisfactory service. These systems have, however, been used almost exclusively for selective signalling on

the so called harmonic principle, in which 55 different frequencies of ringing current are employed in connection with correspondingly tuned bells at the telephones. Now in manual telephone systems a radically different system of selective ringing has been 60 developed for party line service, depending for its selective action partly on the use of separate ground return signalling circuits, and partly on the use of so called pulsating 65 signalling currents of different polarity. This last described system is in common use by the Bell Telephone Company throughout the United States.

Recently a movement has been started 70 with a view to changing over existing manual plants from manual service to automatic service. In carrying out a change of this kind it is of course necessary to discard the manual switch board entirely and substitute an automatic switchboard; but as 75 to the subscribers telephone instruments it is not generally considered necessary to change these. It is a simple operation to install an automatic calling device at each station and the telephones can then be used 80 in connection with an automatic switch board without further change, provided of course that the latter is so designed that it will selectively signal the party line stations in accordance with the system of selective signalling already in use.

In this situation the problem arises of 85 constructing an automatic switchboard or exchange which will successfully signal party lines on which the telephones are constructed and connected according to the above described manual selective ringing principles, and it is this problem that is met and solved by the present invention. The 90 method adopted follows in a general way the four connector group systems of harmonic ringing, already described; but a number of changes and new arrangements have been found to be necessary, and these new improvements together with the operation of 95 the complete system will be described fully hereinafter reference being had to the accompanying drawing.

In the drawing, which is a circuit diagram 100 of the usual character, I have shown sufficient of the equipment pertaining to an automatic telephone switchboard wherewith to establish a connection between a calling

substation A and any one of the four party line substations A' to A⁴ inclusive. In view of the fact that much of the apparatus is well known the detailed circuits have in some instances been omitted and the apparatus is merely indicated in schematic form. The ringing circuits, however, have been shown complete.

The apparatus shown may be briefly described as follows: The substation A is an automatic substation or telephone of well known type and is connected with the central office by the line comprising conductors 11 and 12. At the exchange this line terminates in the individual line or trunk selecting switch indicated by the reference character C. The line switch C has access in the usual manner to a plurality of first selector switches and there may be second and third selectors also, depending on the capacity of the system. The third selectors have access to the connector switches, and one of these selectors is indicated by the reference character D. The selector D, which is indicated by a simple rectangle, as is the line switch C, is one of a group of similar selectors which have access through their ten multiple bank levels to ten groups of connector switches. We need to consider, however, only four of these groups, which is the number of groups required to serve a given group of party lines, and I have shown in the drawing one connector in each of the four groups. These connectors are indicated by reference characters H' to H⁴, inclusive, and connector H' is shown complete. Of the remaining connectors all the circuit details are omitted except the ringing circuits.

The four groups of connectors all have access to the same group of party lines. A party line group may consist of one hundred lines which are connected in multiple in the banks of all the connector switches. Thus the party line comprising conductors 111 and 112, which is the line to which substations A' to A⁴, inclusive, are connected, is multiplied in the banks of connectors H' to H⁴, inclusive, as shown. It will be noticed that the multiple runs straight through the first two groups of connectors, and through the last two groups, but there is a reversal in the line conductors between the second and third groups.

The party line substations A' to A⁴, inclusive, are of well known type and need not be described in detail. Only the substation A' is shown in full, all the circuits of the rest being omitted except the ringing circuits.

The reference character RM, at the lower left hand corner of the drawing, indicates a ringing machine which is assumed to be in continuous operation and which is adapted to impress negative and positive pulsating

currents upon the common ringing leads 98 and 99, respectively, at regular intervals. The connections of these ringing leads and the wiring of the ringing circuits will be described more in detail hereinafter, although it may be stated at this time that the negative lead extends to the connectors in two of the groups while the positive lead goes to the connectors in the other two groups.

It is thought that the operation of the selective ringing system can best be explained by describing the operations which take place when the several stations on the party line shown in the drawing are called from another station and this will now be done. It will be assumed first that the subscriber at substation A desires to call the subscriber at substation A'. When the receiver is removed at substation A the line circuit is closed and the individual line switch C is operated in the usual manner to extend the connection to an idle first selector switch. Successive operations of the dial now cause the operation of the selected first selector, a second selector and a third selector, the latter of which may be the selector D, whereby the calling line is extended to an idle connector in the group of connectors which are adapted to signal the particular substation A'.

Assuming that the connector H' is the switch to be used, when the wipers of the selector D connect with the bank contacts in which conductors 13, 14, and 15 are terminated, the calling line is extended by way of conductors 13 and 15 to the double wound line relay 17 of the connector H, and this relay is accordingly energized to close a circuit for the slow acting release relay 18. The latter relay, upon energizing, prepares the connector for operation in its vertical movement and also, at its upper armature, grounds the release trunk conductor 14, thereby establishing a holding circuit for the preceding switches which are in use in the connection.

The circuit interruptions caused by the next operation of the calling dial cause the line relay 17 to be deenergized a plurality of times and this relay at each deenergization transmits an impulse of current to the vertical magnet 25. The circuit includes the off normal springs 27 and 29 and the winding of the slow acting relay 19, and may be traced without difficulty. By the operation of the vertical magnet the shaft is raised step by step until the wipers 50-52, inclusive, stand opposite the desired level of bank contacts. At the first upward movement of the shaft the off normal springs are shifted and spring 27 is disengaged from spring 29 and is brought into engagement with spring 28, but since the slow acting relay 19 is now energized the

vertical magnet circuit is maintained intact while the series of impulses are being transmitted. When the impulses cease the relay 19 falls back and transfers the operating circuit to the rotary magnet 24.

When the calling dial is operated in accordance with the next and final digit the line relay 17 sends a series of impulses to the rotary magnet 24 and this magnet is 10 operated to rotate the shaft step by step until the wipers 50-52, inclusive, are finally brought to rest in engagement with bank contacts 53-55, inclusive. During the rotation of the switch the slow acting relay 22 15 is energized in parallel with the rotary magnet and maintains its armature continuously attracted. In energized position relay 22 connects the test wiper 51 to the test relay 21, so that if the called line is busy the 20 ground potential on the contact 54 will cause the said test relay to be energized. Relay 21 prepares a locking circuit for itself at its upper armature which is closed when relay 22 deenergizes at the end of the 25 rotary movement, and at its lower armature connects the busy lead 30 to the lower heavy talking conductor, thus giving the calling subscriber a busy signal. We may assume, however, that the line is idle when called, 30 and under these circumstances when the connector completes the connection as described in the foregoing the test wiper 51 will find no ground potential and the test relay 21 will not be energized. Then when 35 the slow acting relay 22 falls back at the end of the rotary movement a circuit is completed from the grounded conductor 14 by way of the upper winding of the switching relay 23, the test wiper 51, test contact 40 54, and the winding of relay 109 to battery. Relay 109 is the cut-off or switching relay of the individual line switch C allotted to the called line and is energized to disconnect the line from its normal battery and ground 45 connections (not shown) in the line switch. The switching relay 23 in the connector is also energized and grounds the test wiper 51, closes a locking circuit for its lower winding, opens the rotary magnet circuit, 50 and finally, at its two outside armatures, connects up the line wipers 50 and 52.

The connection to the called line has now been completed and the ringer at substation A', which, it may be stated, is adapted to 55 respond to negative pulsating current, is operated in the following manner: A circuit for the alternating current relays 113 and 133 at substations A' and A² may be traced from the ringing machine RM by 60 way of negative ringing lead 98, the upper winding of ring cut-off relay 20, the upper talking conductor of the connector, line wiper 50 and bank contact 53 engaged thereby, and line conductor 112 to substation A' 65 where the circuit divides, one branch ex-

tending by way of condenser 115, resistance 114, and A. C. relay 113 to ground and the other branch continuing to substation A² where it extends by way of condenser 135, resistance 134, and A. C. relay 133 to ground. 70 Due to the condensers in the parallel branch circuits to ground at the two substations, alternating currents are set up in the two A. C. relays 113 and 133 and these relays are operated to connect ringers 117 and 137 75 in bridge of the line. As soon as these ringers are connected across the line part of the current will flow through the two ringers in parallel to line conductor 111, and thence by way of said line conductor, bank contact 80 55 and wiper 52 to ground at the lower armature of the ring cut off relay 20. Ringer 117 is adapted to respond to negative pulsating current, as stated, while ringer 137 is adapted to respond to positive 85 pulsating current, and it follows therefore that since the current is being supplied from the negative ringing lead 98 only the ringer 117 will be operated. It is understood of course that in the normal operation of the 90 ringing machine the lead 98 is disconnected at intervals and it is connected to the negative pole of battery, thus causing the ringer 117 to be actuated intermittently in the well 95 known manner.

The subscriber at sub-station A' is now being signalled and his bell will continue to ring until he answers or until the calling subscriber hangs up his receiver. In this connection it should be mentioned that the cut off relay 20 is so adjusted that it will not respond or be operated under ringing conditions. The resistances in circuit at the substations limit the current flow, and relay 20 moreover is provided with a copper 100 slug which greatly reduces the effect of the alternating component of the current. The relay therefore may be readily adjusted so that it will not operate during ringing. When the subscriber at substation A' answers, however, a low resistance bridge is 105 closed across the line through the transmitter and the primary winding of the induction coil and cut off relay 20 is instantly operated, either by current from the battery normally included in the ringing circuit 110 (at any time when this battery is not opposed by the A. C. generator) or by current from the battery to which the lead 98 is connected during the silent periods. 115 Upon energizing relay 20 establishes a locking circuit for itself at its inner armature and at its two outside armatures breaks the ringing circuit and finally completes the talking circuit.

As soon as the talking connection is closed by the ring cut off relay 20, the back bridge relay 16 is energized by current supplied to the called line for talking purposes and 120 reverses the direction of current flow in the 125 130

calling line in the usual manner. This is the customary means provided for operating a meter or coin collect device and being a standard arrangement the circuits are shown this way although no meter or other mechanism is shown. Conversation may now proceed as desired and when the subscribers are through they will both replace their receivers. By the replacement of the receiver at substation A the entire connection is released in the usual manner. When the line circuit is opened the line and release relays 17 and 18 are deenergized and the latter relay closes the circuit of the release magnet 26 through the medium of which the connector H^2 is restored to normal. Relay 18, upon deenergizing, also removes ground from the release trunk conductor 14 and as a result the selector switches included in the connection and also the individual line switch C will be restored, whereupon all the apparatus will be in normal position ready for use in another connection.

Having described the operations involved in signaling the subscriber at substation A', I will now explain briefly how the subscribers at the other substations on the same line are signalled. It was described fully in the course of the preceding explanation how ringers 117 and 137 are connected across the line by the operation of A. C. relays 113 and 133, located at substations A' and A², respectively, and actuated by the application of ringing current to line conductor 112. In the case described ringer 117 was actuated because negative pulsating current was used. It will be seen now that if a connector in the second group, connector H^2 for example, is used to set up the connection positive pulsating current from the positive ringing lead 99 will be applied to the called line instead of negative pulsating current. With this exception all the conditions are the same and it follows that the ringer 137 at substation A² will be operated, for this ringer, as before stated, is adapted to respond to positive pulsating current. The routing of the call by way of a connector in the second group is of course determined by the third from the last digit in the telephone number, and except as to the connector used the connection is established in the same way as in the preceding case.

At substations A³ and A⁴ the A. C. relays are connected from conductor 111 to ground. In order to apply ringing current to this conductor at the exchange the line conductors are reversed in the banks of the two remaining groups of connectors, as shown in the drawing, so that the upper wiper of any connector in these two groups which is operated will connect with conductor 111 rather than with conductor 112.

Since the negative ringing lead supplies ringing current to the connectors of the third group and the positive ringing lead to those in the fourth group, and since the ringers at substations A³ and A⁴ are adapted to respond to negative and positive pulsating currents, respectively, the operation of selectively signalling these last two stations will now be readily understood. Substation A³ is called by way of a connector in the third group, connector H^3 for example, and substation A⁴ is called by way of a connector in the fourth group, such as connector H^4 .

Before closing, particular attention is called to the fact that the circuits and wiring of the connector switches is absolutely uniform throughout the four groups, notwithstanding the fact that the ringing operation performed is different in each group. To be more specific, it is pointed out that ringing current is applied to the called line by way of the upper wiper in all the connectors, and the ring cut off relays in all the connectors are wired exactly alike. This is an extremely desirable feature because in the course of the operation of an exchange the switches are removed from time to time for adjustment and on this account are preferably made interchangeable. The cost of manufacture is also reduced by having the connectors all uniform. To provide for using the upper wiper for ringing in all the connectors, a simple reversal in the lines between the second and third connector groups is all that is necessary. This has been pointed out before. To secure uniform wiring of the ring cut off relays, however, is somewhat more difficult. It will be understood of course that the two windings of one of these relays must be so connected that the current flow in the locking winding will assist rather than oppose the current in the upper winding when the relay is operated by the removal of the receiver on a called line. Since negative pulsating current is used by the connectors in two of the groups and positive by the connectors in the other two groups it will be evident that if the locking windings of all the relays are connected the same the upper windings must be reversed in the case of the relays in two of the groups. This reversal is not done in the connectors, however, but outside. As is well known the incoming trunk conductors and the various power wires, etc., are in practice wired to so called female jacks on the shelf on which the connectors are mounted, and the relays and magnets of the switch are wired to corresponding male jacks which are mounted on the switch frame. When the switch is in position the male and female jacks engage and the various circuits are thus connected up. I provide for each connector switch three extra pairs of jacks.

which in the case of the connector H^2 are indicated by reference characters 72, 73, and 74. The small circles represent the female jacks mounted on the switch shelf and the arrow heads indicate the male jacks which are mounted on the frame of the switch. The ring cut off relay 70 is permanently wired to the three male jacks associated therewith in the manner shown and an inspection of the drawing will show that the ring cut off relays 80 and 90 are wired in exactly the same manner. This is true also of the ring cut off relay 20 of the connector H' in the first group, although the details are not shown. The positive ringing lead 99 supplies ringing current to all connectors in the second and fourth groups and is connected in multiple to the middle female jacks of the extra pairs, as shown in the drawing in the case of connectors H^2 and H^4 . The negative ringing lead is similarly multiplied through the first and third connector groups, but is connected to the lower female jack of each extra set, as shown in the case of connector H^3 . The two vacant female jacks of each set are then strapped together as shown. With the above described arrangement although the connectors are all absolutely alike nevertheless the upper windings of the ring cut off relays in two of the groups are reversed when the connectors are mounted on the shelves, and notwithstanding the use of ringing currents of opposite polarities the upper and lower windings of all the ring cut off relays are properly connected so as to cooperate with each other.

Having described my invention, what I consider to be new and desire to have protected by Letters Patent will be pointed out more specifically in the appended claims.

What I claim is:

1. In an automatic telephone system, party lines, sources of positive and negative pulsating current at the exchange, a plurality of groups of connector switches for calling one of said lines and for connecting said sources thereto for selectively signaling the stations thereon, all of said connectors being alike and interchangeable between groups, and a ring cut off relay in each of said switches having a locking winding independent of the signalling circuit.

2. In an automatic telephone system, a four party line, biased ringers at the stations on said line, sources of positive and negative pulsating current at the exchange, four groups of connector switches for calling said line and for connecting the said current sources thereto for selectively signalling said stations, all of said connectors being alike and interchangeable between groups and a ring cut-off relay in each connector having a winding included in the signalling circuit and a holding winding independent of the signalling circuit.

3. In an automatic telephone system, a four party line, biased ringers at the stations on said line, sources of positive and negative pulsating current at the exchange, four groups of connector switches for calling said line and for connecting the said current sources thereto for selectively signalling said stations, a ring cut-off relay in each connector having a winding included in the signalling circuit when the connector is in use for signalling and a locking winding energized while the connector is in use for talking, and circuit connections outside the said connectors permitting the said ring cut off relays to be all wired and connected in an identical manner, whereby the said connectors are made interchangeable between the said groups.

4. In an automatic telephone system, a four party line, biased ringers at the stations on said line, sources of positive and negative pulsating current at the exchange, four groups of connector switches for calling said line and for connecting the said current sources thereto for selectively signalling said stations, ring cut-off relays in said connectors each having a winding adapted for inclusion in an established signalling circuit and a locking winding, all the said relays being wired and connected within the connectors in an identical manner, and circuit connections outside the said connectors such that both windings of each of said relays cooperate when the said relays are energized.

5. In an automatic telephone system, a party line, sources of positive and negative pulsating current at the exchange, groups of connector switches for calling said line and for connecting the said current sources thereto for selectively signalling said stations, ring cut-off relays in said connectors each having a pull up winding adapted for inclusion in an established signalling circuit and a locking winding, three special terminals on each connector, an outgoing ringing conductor and conductors from the pull up winding of the ring cut-off relay in each connector, the said conductors being connected to the associated special terminals in identically the same way in each connector, other terminals for each connector engaged by said first named terminals when the switches are mounted on the switchboard, and circuit connections at the said other terminals associated with each connector including an incoming ringing conductor connected to one of them such that both windings of each ring cut-off relay will cooperate when the said relays are energized.

6. In an automatic telephone system, a party line, biased ringers at the stations on said line, sources of positive and negative pulsating current at the exchange, groups of connector switches for calling said line and for connecting the said current sources there-

to for selectively signalling said stations, side the said connectors such that both windings cut-off relays in said connectors each having a winding adapted for inclusion in an established signalling circuit and a locking winding, all the said relays being wired and connected within the connectors in an identical manner, and circuit connections out-

10
ings of each of said relays co-operate when the said relays are energized.

Signed by me at Chicago, Cook County, Illinois, this 28th day of June, 1920.

TALBOT G. MARTIN.
